UNITED STATES PATENT OFFICE.

WILLIAM A. UTTZ, OF ARDMORE, OKLAHOMA.

DESIGN FOR A RADIATOR NOVELTY.

51,976.

Specification for Design. Patented Apr. 16, 1918.

Application filed January 21, 1918. Serial No. 213,077. Term of patent 14 years.

To all whom it may concern:

Be it known that I, WILLIAM A. UTTZ, a citizen of the United States of America, residing at Ardmore, in the county of Carter and State of Oklahoma, have invented a new, original, and ornamental Design for Radiator Novelties, of which the following is a specification, reference being had to the accompanying drawing, forming part thereof.

The figure is a side elevation of a radiator novelty which is a representation of "Uncle Sam", sitting on a cannon shell, holding a flag in one hand and scales of justice in the other hand.

I claim:

The ornamental design for a radiator novelty, as shown and described.

WILLIAM A. UTTZ.
